INVALID'S BED

Marvel Beem, West Los Angeles, Calif., assignor
of one-half to The Beem Foundation, Los Angeles, Calif., a charitable trust of California

Application September 1, 1945, Serial No. 613,985

5 Claims. (Cl. 5—90)

1

This invention relates to beds, and has as its general object to provide a bed having incorporated therein all of the conveniences necessary for the care of an invalid patient. The invention is particularly useful in hospital and invalid's beds.

One of the objects of the invention is to provide a bed having a flushable toilet incorporated therein, eliminating the necessity for the use of a bed pan. More specifically, the invention aims to provide a bed having a normally covered opening to which a toilet is adapted to be presented, the toilet being normally concealed beneath the bed, in a lowered position. An important object of the invention is to provide a bed of this type wherein the existence of the toilet opening does not in any way detract from the comfort of the patient when resting in the bed. To this end, the invention contemplates an arrangement wherein the toilet and toilet opening are disposed at one side of bed, separate and apart from the major portion of the bed in which the patient normally rests.

A particular object of the invention is to provide a bed having a removable bed bottom which is adapted to be transferred to an ambulatory cart for transporting the patient from the bed to other parts of a hospital. In connection with this object, the invention contemplates the provision of a bed structure wherein the toilet portion of the bed is fixed to the bed frame and the main portion of the bed has the removable bed bottom portion just mentioned.

A further object of the invention is to provide a flushable toilet arrangement in which the toilet bowl, in its operative position, is so inclined as to permit the body of the patient to be supported in a proper relation to the bowl, and in a comfortable reclining position. Consequently, the invention has as a further object to provide a bed wherein the toilet portion of the bed has a bed bottom that is articulated, including a back rest, a thigh portion and a leg rest adapted to be elevated to inclined positions in which they cooperate to form a reclining seat for the patient. The invention also contemplates an arrangement wherein the main bed bottom portion of the bed is likewise articulated, and wherein common elevating mechanism is employed for raising the respective sections of both of these bed bottom portions of the bed simultaneously.

A further object of the invention is to provide a normal lift mechanism for elevating the respective portions of the bed, which lift mechanism is arranged to move out of engagement with the

2

removable bed bottom portion so as to permit it to be removed from the bed.

Another object of the invention is to provide a bed in which the toilet bowl is adapted to be projected horizontally from beneath the bed for use by an ambulatory patient.

A further object is to provide a bed in which the toilet bowl is adapted to conform to the angularity of the thigh section of the toilet seat portion of the bed.

Another object is to provide a bed which, in addition to the above mentioned features, incorporates a lavatory that is normally concealed beneath the bed and is adapted to be moved to a position above the bed for use by a patient in the bed.

Another object is to provide a bed which, in addition to the foregoing features, is provided with a trapeze by means of which the patient may move himself from the main portion of the bed to the toilet portion of the bed, and which incorporates mechanism for shifting the trapeze from a normally inoperative position in which it substantially conforms to the outline of the head of the bed to an operative position projected over the bed.

Another object of the invention is to provide a bed in which the toilet opening is normally covered by a cover that is provided with mechanism for automatically moving it to a position in which it permits access to the toilet, as the result of the elevation of the toilet to the toilet opening.

Other objects of the invention will appear in the ensuing specification when considered in connection with the appended drawings, wherein:

Fig. 1 is a plan view of a hospital bed embodying the invention;

Fig. 2 is a longitudinal vertical sectional view of the toilet portion of the bed, taken on the line 2—2 of Fig. 1, the articulated bed top, the toilet and the trapeze all being in elevated positions;

Fig. 3 is a fragmentary longitudinal sectional view taken on the line 3—3 of Fig. 1;

Fig. 4 is a transverse sectional view of the bed taken on the line 4—4 of Fig. 2, illustrating the transfer of the removable top portion of the bed onto an ambulatory cart; and

Fig. 5 is a transverse sectional view showing the lavatory in its elevated position.

As an example of one form in which the invention may be embodied, I have shown in the drawings a bed including a head 9, a foot 10, a removable bed bottom portion 12 comprising three sections 13, 14 and 15 hinged together at 21 and

22, and a narrow bed bottom portion 17 comprising parts 18, 19 and 20 hinged together at 23 and 24. The hinges 22 are connected to a sub-frame 16 (Fig. 3) and the hinges 24 are connected to fixed longitudinal rails 11, 11'.

The thigh section 19 of the toilet portion of the bed bottom is provided with an opening to receive the toilet bowl 25. The toilet bowl 25 is adapted to move vertically from a position near the floor to the raised position shown in Fig. 2, in which position it projects upwardly through the opening in the thigh section 19. The upper extremity of the bowl is, in this position, sufficiently below the upper surface of the mattress 26 (indicated in broken lines in Fig. 2) so that the compression of the mattress under the patient's weight will bring the thighs of the patient into contact with the bowl.

The opening in the thigh section 19 is normally covered by a cover 27 which has a frame portion 28 extending downwardly therethrough and hinged at 29 to brackets 30 that are secured to the side frame members of the thigh section 19. Thus the cover 27 may swing upwardly to a position in which the frame portion 28 contacts the outer rail of the thigh section 19, in which position the cover 27 will be projected beyond the side of the bed. The frame portion 28 includes one or more compartments 28a for holding toilet tissue or the like.

The bowl 25 is attached to one end of a waste pipe 31 which is of flexible tubing. The other end of the pipe 31 is connected to a sewer outlet 32. For flushing the toilet, I provide a connection 33 to a flexible water inlet 34 which in turn is connected to a water supply pipe 35. The connection 33 may include a valve which is controlled by a solenoid 36.

The bowl 25 is carried on the end of a swinging yoke 36. One end of the yoke 36 is hinged at 37 to the bowl 25 and the other end of the yoke is hinged at 38 to a bracket 39 which is pivoted, on a vertical axis, between a pair of bearings 40 and 41 respectively. The bearings 40 and 41 are secured to the fixed frame mechanism of the bed.

Journalled in the bracket 39 is a screw shaft 42 on which is threaded a follower nut 43. Nut 43 is held against rotation by a slideable connection with a channel 44 in the bracket 39, and is caused to travel vertically when the shaft 42 is rotated. For rotating the shaft 42, I provide a reduction gear 45, driven by a motor 46 carried on the head member 9. The gear 45 may include a worm on the shaft of the motor 46 and a worm gear secured on the screw shaft 42.

A pair of chains 47 are attached to the follower nut 43, extend over idler sprocket 48 on the bracket 39, and are attached at their other ends to a yoke 49 that in turn is attached to the yoke 36. It will now be apparent that operation of the motor 46 will cause the nut 43 to travel vertically on the shaft 42, thereby raising or lowering the bowl 25.

A coil spring 51, under tension between the bowl 25 and the yoke 36, tends to maintain the bowl 25 in a neutral position with reference to the yoke 36. From this neutral position, the bowl 25 may be tilted in either direction so as to conform to the angularity of the thigh section 19. Such tilting movement is caused by engagement of a plurality of rollers 52, carried by the bowl 25, with the underside of the thigh section 19.

When the bowl 25 is in its lowered position, it

may be projected horizontally from beneath the bed by the swinging of the entire bowl suspension unit including the bowl 25 and the yoke 36, bracket 39 and chain 47, about the axis of the bearings 40, 41. This provides for use on the floor, by an ambulatory patient.

The elevation of the bowl 25 automatically moves the cover 27 to its open position. This is effected by means of an arm 53, pivoted at 54 to a bracket 55 that is secured to the fixed frame 19, and a link 56 universally connected at its respective ends to the arm 53 and to the frame portion 28 of the cover 27.

For elevating the articulated sections of the toilet portion 17, of the bed top, I provide pairs of rack bars 57 and 58 respectively the upper ends of which are adapted to engage in sockets 59 and 60 respectively secured to the under sides of the top sections 18 and 20. Each of the rack bars 57 and 58 extend through guide members 61, are meshed therein with pinions 62, and have bearing engagement with idler rollers 63. The pinions 62 are mounted on shafts 64 which extend transversely beneath the bed and are each driven by a motor 65, through a reduction gear 66.

The articulated sections of the removable bed bottom unit 12 are likewise adapted to be elevated by lift units identical to those just described and referred to by the same reference numerals. These lift units are connected to the same shaft 64 which drive the lift units for the toilet portion of the bed top.

In their retracted positions, the rack bars 57 and 58 are lowered sufficiently so that their upper ends are withdrawn from the sockets 59 and 60 and clear the lower sides of the longitudinal rails of the sub-frame 16. This permits the removable top unit 12 to be moved off the bed without interference from the lift mechanism.

The trapeze comprises a horizontal bar 67 having a pair of normally vertical side arms 68 which are carried by normally horizontal side arms 69. The ends of the arms 69 are mounted upon a shaft 70 which is journalled in the fixed frame member 11, 11', 11''. In the lowered position of the trapeze, the arms 69 extend horizontally alongside the rails 11, 11'', in spaces between these rails and side panels 72 and 73 of the bed. The arms 68 extend upwardly along the side extremities of the head 9 of the bed, and the cross-bar 67 extends along the upper edge of the head 9. This indicated in dotted lines in Fig. 2.

The sub-frame 16 is provided with rollers 75 operating in tracks 76 which are secured at their ends to fixed frame members 11 and 11' and extend transversely of the bed. The sub-frame 16, top sections 13, 14 and 15, and the mattress 77 supported thereon, collectively constitute the unit 12 which is removable from the bed onto an ambulatory cart 78. Cart 78 has tracks 79 which are adapted to register with the tracks 76 when the cart is moved to the proper position alongside the bed as shown in Fig. 3, and the removable bed bottom unit 12 may then be simply rolled transversely from the bed onto the cart 78.

As illustrated in Fig. 3, the rollers 75 are mounted in end members 80 of the sub-frame 16, which end members 80 lie directly above the tracks 76.

The fixed frame members 11, 11', and 11'' are secured and supported at their ends upon the head 9 and foot 10 in any suitable manner, as by resting upon angle brackets 81 secured to the head 9 and foot 10.

The toilet portion 17 of the bed bottom is per-

manently attached to the bed by the hinging of the sections 19 and 20 to brackets 82 which are secured upon the fixed frame rails 11' and 11''. These brackets are of sufficient height to bring the hinges 24 in alignment with hinges 22. The head and foot rests 20 and 18 are supported upon transverse frame members 83, 84, and 85 respectively when the sections of the toilet portion of the bed bottom are in their lowered, horizontal position.

Secured to the shaft 70 is a lever 86 which projects downwardly. At the lower end of the lever 86 is pivoted at 87, a sleeve 88. A shaft 89 extends through the sleeve 88 and has affixed thereto a stop collar 90 which is adapted to push against the sleeve 88 for rocking the lever 86 to rotate the shaft 70 and lift the trapeze to the operative position shown in Fig. 2. The shaft 89 forms part of a screwjack 91 which is driven, through reduction gearing 92, by an electric motor 93. The gearing 92 is pivoted at 94 to the fixed frame member 11.

In its elevated position, the trapeze bar 67 extends above the bed in the proper position to permit the patient to reach up and grasp it in order to swing himself laterally from the main bed portion 12 to the toilet portion 17.

I provide a lavatory 95, mounted upon the upper ends of the vertical arms 96 of a pair of tubes 97 which extend horizontally parallel to each other. The ends of the tubes 97 are capped at 98. A water supply tube 99 is connected to one of the tubes 97 and a waste disposal tube 100 is connected to the other tube 97. The tubes 99 and 100 are flexible and are connected respectively to a water supply pipe 101 and a sewer outlet pipe 102. One of the tube members 96 carries water to the lavatory bowl 95 and the other is connected to the drain outlet thereof.

The tubes 97 are supported on the ends of arms 103 to which they are pivoted. The arms 103 are mounted on shafts 104 of a pair of reduction gear units 105. An electric motor 106 drives the gear units 105 through a shaft 107.

Operation of the motor 106 in one direction will swing the arms 103 clockwise (as viewed in Fig. 4), projecting the lavatory bowl 95 through an opening 108 in the panel 73. The opening 108 is normally closed by a door 109 which is hinged in the panel 73. As the movement of arms 103 continues, bowl 95 will move upwardly and then as the arms 103 swing past the top center, the bowl 95 will move back toward and over the bed, to the position indicated in Fig. 5.

The motors 46, 65, 93 and 106 are all reversible electric motors, so the various units may be operated in both directions.

The lavatory unit includes a utility tray 111 which may assume a position covering the bowl 95, in which position, it may be utilized as a tray for supporting dishes of food, cosmetics, toilet accessories and implements, etc. The tray 111 is hinged to the lavatory at 112, and when the lavatory is to be used, the tray 111 is swung to the position shown in Fig. 5, in which it depends from the hinge 112 and covers the back of the lavatory.

The panel 72 has a hinged section 115 which is adapted to swing outwardly to permit the horizontal swinging of the bowl 25 from beneath the bed. The section 115 is hinged to the head 9 of the bed at 116.

Provision is made for heating the bed by the circulation of hot air from beneath the bed upwardly into the space beneath the covers of the

bed. For this purpose, I provide a heater 117 which is disposed in the space below the bed. Between the narrow top portion 17 and the removable top portion 12 of the bed, there is normally a narrow space 118, through which hot air from the heater 117 may rise into the space beneath the covers of the bed.

I claim as my invention:

1. In a bed, a fixed, non-portable frame, a bed bottom comprising two separate bottom portions one permanently attached to said fixed frame and having a toilet facility incorporated therein, said toilet facility including flushing and sewer connections, and the other comprising a main patient supporting bottom portion normally arranged alongside said one portion to form therewith a substantially continuous supporting surface on which the patient may readily move from said main supporting portion onto said one portion for use of the toilet facility, said main supporting portion being detachable from said fixed frame for transportation of the patient away from the bed, and means mounting said main supporting portion on said fixed frame for horizontal translational movement off of and back onto the fixed frame.
2. In a bed, a frame, a pair of separate sectional bed bottom portions each including a back rest and thigh section carried by said frame and hinged together for elevating movement toward each other and a leg rest hinged to said thigh section to provide a knee joint, said bed bottom portions being arranged side by side to normally provide conjointly a substantially continuous bed surface, one of said bed bottom portions providing a normal resting surface and the thigh section of the other providing a toilet seat and having a toilet opening, a toilet bowl beneath said other bottom portion, cooperable with said opening, and lift mechanism having common drive mechanism and parts adapted to simultaneously elevate both of said bed bottom portions in continuously registering relation, whereby a person may, at any stage of such elevation, easily move from said normal resting surface onto said toilet seat and back.

3. In a bed, a frame, a pair of separate sectional bed bottom portions each including a back rest and thigh section carried by said frame and hinged together for elevating movement toward each other and a leg rest hinged to said thigh section to provide a knee joint, said bed bottom portions being arranged side by side to normally provide conjointly a substantially continuous bed surface, means on said frame and one of said bed bottom portions providing for horizontal lateral translational movement of the latter off of said frame whereby said one bed bottom portion may be moved onto a transporting cart, said one bed bottom portion providing a normal resting surface and the thigh section of the other providing a toilet seat and having a toilet opening, a toilet bowl beneath said other bottom portion, cooperable with said opening, and lift mechanism having common drive mechanism and parts adapted to simultaneously elevate both of said bed bottom portions in continuously registering relation, whereby a person may, at any stage of such elevation, easily move from said normal resting surface onto said toilet seat and back.
4. A bed comprising a fixed frame, a removable frame, roller mechanism supporting said re-

5. In a bed, a frame, a pair of separate sectional bed bottom portions each including a back rest and thigh section carried by said frame and hinged together for elevating movement toward each other and a leg rest hinged to said thigh section to provide a knee joint, said bed bottom portions being arranged side by side to normally provide conjointly a substantially continuous bed surface, means on said frame and one of said bed bottom portions providing for horizontal lateral translational movement of the latter off of said frame whereby said one bed bottom portion may be moved onto a transporting cart, said one bed bottom portion providing a normal resting surface and the thigh section of the other providing a toilet seat and having a toilet opening, a toilet bowl beneath said other bottom portion, cooperable with said opening, and lift mechanism having common drive mechanism and parts adapted to simultaneously elevate both of said bed bottom portions in continuously registering relation, whereby a person may, at any stage of such elevation, easily move from said normal resting surface onto said toilet seat and back, said elevating parts for said one bed bottom portion being retractable to allow said movement off of said frame.
6. A bed comprising a fixed frame, a removable frame, roller mechanism supporting said re-

movable frame on said fixed frame for horizontal translational movement whereby it may be removed from the bed, a bed bottom supported upon said removable frame, said bed bottom comprising a head section and a thigh section hinged to the removable frame and a foot section hinged to said thigh section, and elevating means carried by the fixed frame and adapted to move from a position disposed wholly below the plane of said removable frame so as to permit free 10 movement thereof horizontally, to a position wherein it contacts a bed bottom section from below and raises it to an inclined position.

5. A bed comprising a fixed frame, a removable frame, means supporting said removable 15 frame for horizontal translational movement on said fixed frame, whereby it may be removed from the bed, and a sectional bed bottom carried by said removable frame, said bed bottom comprising a head section and a thigh section hinged to the removable frame and a foot section hinged 20 to said thigh section.
